UNITED STATES PATENT OFFICE.

OTEY R. KIRKPATRICK, OF FORT WORTH, TEXAS.

WRENCH.

1,356,923.

Specification of Letters Patent. Patented Oct. 26, 1920.

Application filed December 16, 1919. Serial No. 345,310.

To all whom it may concern:

Be it known that I, OTEY R. KIRKPATRICK, a citizen of the United States of America, residing at Fort Worth, in the county of 5 Tarrant and State of Texas, have invented certain new and useful Improvements in Wrenches, of which the following is a specification.

My invention relates to wrenches and particularly to wrenches which can be used both as pipe wrenches and wrenches for general purposes, and the object is to provide a wrench which can be instantly adjusted and which can be quickly adjusted by the 10 same hand which is using the wrench, and another object is to provide a wrench which is both readily adjustable and which has the requisite strength for any ordinary work. Other objects and advantages will be fully 15 explained in the following description and the invention will be more particularly pointed out in the claim.

Reference is had to the accompanying drawings which form a part of this application.

Figure 1 is a side elevation of the wrench. Fig. 2 is a side elevation, partly in section. Fig. 3 is a view of the back edge of the wrench.

Similar characters of reference are used to indicate the same parts throughout the several views.

The improved wrench has a power member in two parts,—a jaw member 1 and a handle member 2. The member 1 has a toothed jaw 3 integral therewith. The wrench has an adjustable jaw member 4 provided with a toothed jaw 5 integral therewith. A yoke 6 is attached to the member 4 by a rivet 7 and engages the member 1 loosely and holds the members 1 and 4 in their relative positions. The members 1 and 2 are locked and attached together by means of interlocking parts. The member 2 has a cavity 8 extending entirely therethrough transversely and has an opening 9 in the end thereof. The member 1 has a reduced member 10 forming a shank for inserting in the cavity 9 and the shank 10 has a spring 40 seat 11. The shank 10 is secured in the cavity 9 by a rivet 12. The rivet 12 extends entirely through the member 2 and shank 10 and also through both sides of a yoke 13 and so secures the yoke and the two members 1

and 2 together. The yoke 13 engages the 55 member 4 loosely and serves to hold the member 4 in its position relative to the members 1 and 2. The member 4 is provided with teeth 14 which have each one flat face at right angles to the member 4. The movable member 4 is locked to the power member, composed of parts 1 and 2, by a plunger lock 15 which moves at right angles to the member 4. The lock 15 is held in engagement with the movable member 4 by a spiral 60 spring 16 which is mounted in the cavity 8 and bears against the seat 11. The lock 15 may be released from the member 4 by lugs 17 which are rigid therewith and project through slots 18 in the member 2. The lugs 70 17 are so positioned that they can be actuated by a thumb of the hand which is using the wrench. The lock 15 has teeth corresponding to the teeth 16 of member 4. The lock 15 is not supported on a lever or a 75 pivot bolt, but when strain comes on the member 4, the lock is held in place by the walls of the cavity 8 in the member 2. The member 4 will be immovable when the lock 15 is engaging this member. The spring 16 80 normally holds the lock in engagement with the member 4, but is readily released therefrom by a pressure on the release lugs 17 or either one of them. The member composed of parts 1 and 2 will have the necessary power by reason of the interlocking of these members and the yokes 6 and 13. The member 4 moves freely through the yoke 13 and the member 1 moves freely through the yoke 6. 90

What I claim is:—

A wrench of the type described comprising a handle shank, an outer jaw having a relatively short inner shank pivotally mounted at its inner end to the outer end of 95 the handle shank, an inner jaw having a toothed shank slidably associated with the outer jaw and handle shanks, a transversely sliding rack catch carried by the handle shank for engagement with the teeth of the inner jaw shank, and a spring interposed between the rack catch and the inner end of 100 the outer jaw shank to hold the rack catch projected.

In testimony whereof, I set my hand, this 105 tenth day of December, A. D. 1919.

OTEY R. KIRKPATRICK.
